[57] ABSTRACT

[22] Filed: Oct. 18, 1973

The invention concerns a device for the transfer of sealing capsules as well as equipment for positioning these capsules and feeding a bottle capping machine to operate this device.

[21] Appl. No.: 407,495

The device consists of a hand on which is mounted a nozzle, an arm clamped onto an axle and articulated on the hand, a revolving plate holding the axle loosely mounted; a kinematic linking chain controls the arm but it is disengaged while the capsule is being positioned, the control being then assumed by a cam; a kinematic loose chain (a chain with no connection) maintains the position of the hand, a differential level permitting the introduction of a rotation through 90° by a cam during the positioning of the capsule.

[30] Foreign Application Priority Data

Oct. 18, 1972 France 72.36820

The invention applies to the transfer and placing of sealing capsules.

**DEVICE FOR TRANSFER AND POSITIONING
SEALING CAPSULES FOR FEEDING A BOTTLE
CAPPING MACHINE**

The present invention relates to a device for the transport of sealing caps and to an apparatus for placing these caps in position and supplying a bottle capping machine in the operation of this device. This device and apparatus are particularly intended for positioning so-called "long caps" on bottles with long necks and wide mouths, which generally contain gasified wines such as champagnes or sparkling wines.

The invention is concerned broadly with apparatus for the dressing of the bottles.

The sealing caps comprise a relatively large frustoconical skirt closed on its small base by a disc. They are delivered to the users nested one inside the other to constitute stacks of a predetermined length known as "sticks."

In the dressing of bottles of still wine whose neck is of a relatively small diameter, short, slightly conical caps are used. These caps have a diameter which is only slightly larger than that of the top part of the neck of the bottles, and the crimping of the caps is brought about by substantially uniform shrinking of the metal which is sufficiently light to cause only a very slight deformation of the illustrations or inscriptions which are generally printed on the capsules. This construction is effected by means of knurled wheels.

The dressing of bottles of gasified wines which have a wide neck requires much longer caps, whose angle at the top of the frustoconical skirt is much larger, so that the shape of the skirt differs significantly from that of the outer surface of the neck of the bottle to be capped. The crimping is brought about by a bottle capping machine comprising two groups of elastomeric curbs, working successively. The first group, generally composed of four curbs exerting a strong radial pressure, stamps the capsule following two pairs of identical surfaces which are separated from each other by four vertical pleats; these pleats absorb the excess of metal. The second group of curbs is intended to flatten the pleats formed by the first group, to give the bottle dressing a homogeneous effect.

It will be seen that, when the illustrations or inscriptions are printed onto this sort of capsule, it is important that they should not be in the region of the pleats, which would make them partially or totally illegible. On the contrary, it is necessary for them to be in the middle of the two larger surfaces stamped by the curbs of the first group, the pleats which define each of these surfaces being flattened down one on each side thereof.

It is therefore vital to carry out a careful orientation of each cap as it enters the bottle capping machine.

According to a known process, there is printed onto the cap an indicator discernible by a photo-electric cell, and the cap is orientated by turning the bottle, before crimping, until a signal emitted or transmitted by the cell indicates the correct position. The use of this process is wasteful in time and the necessary apparatus is costly.

The indicator may also consist in a deformation of the cap which is more easily discernible by a simple apparatus. French Pat. No. 2,036,244 describes asymmetric caps whose cross-section comprises a circular part subtending an angle of 270° and a V-shaped part

shaped as two right angles forming between themselves an angle substantially equal to 90°, and tangentially joined to the circular part. The piece of the capsule corresponding to this V-shaped part is called the mouth. The pictures or inscriptions are printed onto this circular section, with a displacement of 90° relative to a generator of the mouth junction. The base of the capsule may be circular or have various other shapes.

An object of this invention is to provide a device for transporting sealing caps.

Another object of the invention is to provide an apparatus for positioning such caps and for supplying a bottle-capping machine which uses this device.

The device and the apparatus allow the bottle-capping machine to be fed by bottles on which caps are placed whose "mouths" are orientated in a rigorously constant and known direction.

According to the invention, the transporting device comprises a sucker for holding a cap by means of a vacuum, a hand on which the sucker is mounted, an arm held on a first spindle and joined to the hand by a second spindle, and a plate keyed to a shaft pivoting in a fixed hub and carrying the first spindle which is idly mounted thereon. A kinematic chain with a ratio of -1 controls the movements of the arm, and contains a clutch which engages the chain while a cap is being taken up by the sucker, and disengages it while the cap is positioned on the neck of a bottle, an outside cam controlling the movements of the arm. A kinematic chain of nil ratio maintains the position of the hand, and comprises a clutch which engages the chain during the taking up of the cap and disengages it during the positioning of the capsule, at which time a fixed cam controls the movements of the hand.

The apparatus for positioning the caps and feeding the bottle capping machine, uses the above device and itself includes a device for transporting bottles comprising a moving chain and a variable pitch feed screw for distributing the bottles, a track constituting rolling path and provided with a guide slot closed on itself, at least one carriage carrying two curbs constituting pincers capable of seizing a bottle, at least two horizontal guide rollers engaged in the slot so as to guide the carriage, and finally an endless chain insuring the movement of the carriage.

The invention thus defined is explained by examples illustrated by the accompanying drawings in which:

FIG. 1 is an overall view in side elevation of an apparatus according to the invention for positioning the caps and feeding a bottle capping machine;

FIGS. 2 to 13 show a device for the correct presentation of the caps; FIG. 2 is a side elevation of the device; FIGS. 3, 4 and 5 are cross-sections of FIG. 2 by the vertical planes III-III, IV-IV and V; FIG. 6 shows a detail of FIG. 5; FIG. 7 is a partial section of FIG. 2 along the line VIII-VIII; FIG. 8 is a section by a vertical axial plane intended particularly to show the cap distribution or; FIG. 9 is a view of FIG. 8 from direction IX; FIG. 10 is a section of FIG. 8 along the line X-X; FIGS. 11 and 12 are cross-sections of FIG. 10 along the lines XI-XI and XII-XII, respectively; FIG. 13 is a section of FIG. 12 along the line XIII-XIII.

FIGS. 14 to 22 show the device for the transporting of the caps; FIG. 14 is an axial section; FIG. 15 is a side elevation seen from the right-hand side of FIG. 14 assuming certain parts to have been removed; FIG. 16 is

a side view seen from the left-hand side of FIG. 14; FIGS. 17 and 18 are cross-sections of FIG. 15 along the lines XVII—XII and XVIII—XVIII respectively, FIG. 19 is a side view of a detail of FIG. 14; FIG. 20 is a cross-section of FIG. 19 along the line XX—XX; FIGS. 21 and 22 are detailed views; FIG. 21 is a side elevation seen from a direction along an axis of FIG. 14; FIG. 22 is a side view partly in section corresponding to FIG. 21:

FIGS. 23 to 31 show a device for transporting bottles; FIG. 23 is a plan view of a carriage; FIG. 24 is a cross-section of FIG. 23 along the lines XXIV—XXIV; FIG. 25 is an enlargement of a detail of FIG. 24; FIG. 26 shows a carriage seen from below and FIG. 27 is a cross-section of FIG. 26 along the line XXVII—XXVII; FIG. 28 is an overall view, in plan, of the device for transporting the bottles; FIG. 29, 30 and 31 are cross-sections of FIG. 28 along the lines XXIX—XXIX, XXX—XXX and XXXI—XXXI, respectively:

FIG. 32 is an overall plan view of the machine for transporting the bottles and crimping on the caps, the top of the machine being assumed to have been removed:

FIG. 33 is a sketch showing how the track of the exterior cam of the transfer device may be obtained;

FIGS. 34 and 35 are sketches showing the components of the two kinematic chains of the transfer device.

On these views, identical components have been represented by identical reference numbers.

According to FIGS. 1 and 32, the apparatus for positioning the sealing caps and for feeding the bottle-capping machine comprises:

a capsule presenting device 1, the purpose of which is to present horizontally a stick of caps 91, the second cap in the stick being held back so as to allow the first caps 913 to be taken up (this device is not part of the invention);

a device 2 for the transfer of caps, insuring the taking-up of the first cap presented horizontally by the device 1, the transporting of that cap and its placing in a vertical position on the mouth of a bottle 952;

a device 3 for transferring bottles; and

a bottle-capping machine 4 of conventional crimping type.

The device 1 for presenting the caps is illustrated by FIGS. 2 to 13. It comprises a device 11-12 for moving the stick of caps forward and a device 13 for distributing the caps one by one. The device 1 is mounted on a fixed chassis 100 essentially comprising a horizontal plate 101 on which is fixed a lower vertical plate 102 with an upper vertical plate 104 in front of it.

The device for pushing forward the stick of caps 91 comprises a V-shaped groove 11 and a control device 12.

The groove 11 is made up of a section 111 involving a longitudinal indentation, V-shaped like the V constituted by the stick of caps, and bounded by two surfaces 1111 and 1112. This section is provided with two channels, one channel 1113 in its front region, the other channel 1114 at the furthest point to the rear, and two slots 1115 and 1116 parallel respectively with the faces 1111 and 1112. The groove also contains two conveyor belts 112 and 113; supported at the front by two driven pulleys 1121 and 1131 respectively housed in the channel 1113 and at the back by two idle pulleys 1122 and 1132, respectively, housed in the channel 1114. The

working length of each belt is parallel with one or the other of the two faces 1111 and 1112 and moves a small distance above them, while the return length moves in the respective slots 1115 and 1116.

5 The front pulleys 1121 and 1131 are interlocked with a pair of conical gears 1123 and 1133. On the spindle 1124 of the pulley 1121 is wedged a ratchet wheel 1141 fixed to a lever arm 1142 which is itself joined to an eccentric plate 1145 by way of a coupling rod 1144. The eccentric plate 1143 is mounted on a shaft 1145 mounted in a bearing 1146 and rotated by a bevel gear 1147, controlled by a chain and sprocket 1148. The bearing 1146, the bearing in which the spindle carrying the wheel 1148 turns, and the drive sprocket 1148 for the bevel gear 1147 are mounted on a support 103 fixed on the horizontal plate 101.

Above the groove 11, a control device 12 prevents the stick of capsules from losing contact with the belts 111 and 112.

20 This control device consists of two rollers 1211 and 1212 carried by two plates 1221 and 1222 held together by a brace 1223 and carried by a control arm 123 capable of pivoting around a spindle 1231 which is screwed onto the vertical plate 102. The position of this arm 123 can be regulated by means of a knurled knob 1241 which turns a threaded rod 1242 engaging with a screw nut 1243 carrying an abutment on which the end of the arm 123 rests. The position of the arm 1245 can be locked by means of a handle 1246.

25 At the forward part of the section 111 is fixed a front blade 1117 controlled by a jack 1118.

The cap distributor comprises a jack 132 fixed to a supporting plate 131 which is itself screwed onto a vertical plate 104 by means of oval holes 1311 and screws 35 1312. A height regulator can be activated by the action of a knurled knob 1313 acting on a threaded rod 1314 engaged in a screw 1315 fixed to the supporting plate 131.

30 The jack 132 has a stem 1321 at the end of which a support 133 is fixed, and this carries on its lower face a stop 1331 and on its upper face two corner pieces 1332 and 1333 each of which is capable of engaging with a roller 1341, 1342, rotatable around a horizontal spindle fixed to a clamp 1343, 1344. Each of these supports can pivot around and slide on a vertical spindle 1345, 1346 and at the opposite end from that which holds the roller it carries a grip 1347, 1348. On either side of these grips are two nozzles 1351 and 1352. These last, as well as the spindles 1345 and 1346 are supported by a casting 1353 tapped so as to permit the feeding of compressed air to the nozzles. A threaded rod 1334 insures the control of the support 133 and of the corner pieces 1332 and 1333.

35 55 The device 2 for transfer of caps illustrated in FIGS. 14 to 22, is installed on a chassis 200 consisting of a rear plate 2001 on which are bolted a frame 2002, comprising four U-shaped sections and a fixed boss 202 in which a hollow shaft 201 can turn. Between the shaft and the boss are interposed three rotating joints 2021 allowing the passage of compressed air and vacuum circuits.

60 65 On the hollow shaft 201 is keyed a plate 20 set in motion by a uniform rotation transmitted by a toothed wheel 2011 wedged on the shaft.

The plate 20 carries two identical devices 21 and 22 for transporting caps. In the following description each part is indicated by a reference of which the first two

numbers reproduce the reference of the corresponding device and of which the other numbers are specific to the part under consideration. For example, the references 2151 and 2251 represent two identical parts, i.e., air holes, of which the first belongs to the device 21 and the second to the device 22.

Each device consists of a bearing 2110 crossing the plate 20, the two bearings 2110 and 2210 of the two devices being displaced by 180° with respect to the shaft 201, according to FIGS. 1 and 22. In this bearing 2110 can pivot a spindle 211 on which an arm 212 is wedged by means of locking pieces constituted by a cross-piece 2121 keyed onto the spindle and a cover 2122. These locking pieces are blocked by a screw 2123 which permits angular regulation. The arm 212 carries, at its free end, a spindle 2126 on which is articulated a support known as a "hand" 213 which carries a sucker 2151. The distance between the spindles 211 and 2126 is equal to that between the spindles 211 and 201.

On the fixed boss 202 are firmly mounted, from back to front: a toothed wheel 2022 which forms the beginning of a kinematic linking chain (-1) controlling the movements of the arm 212, a cam 2023 which produces a differential rocking movement of the hands, and pinion 2024 which is the first member of a kinematic chain of nil ratio controlling the hand 213. These three parts are common to the two devices 1 and 22 respectively. The kinematic chain of -1 ratio which controls the movements of the arm 212 consists of an intermediate pinion 2115 mounted on a spindle 2116 fixed on the plate 20. This pinion 2115 meshes with the fixed wheel 2022 and drives a pinion 2114 keyed to a ratchet wheel 2113 having a single tooth 21131; the whole is loosely mounted on the spindle 211. The latter also carries clamped thereon a boss 2111 on which is mounted a pawl 2112 capable of engaging with the tooth 21131 of the ratchet wheel 2113. The boss 2111 drives the arm 212 which is wedged on the spindle 211. The tooth ratio of the wheel 2022 to the pinion 2114 is 2:1; on the other hand, the distance between the spindles 211 and 2126 is equal to the radius of the circumference on which the spindle 211 moves, so that the spindle 2126 describes a right angle. Thanks to the ratchet wheel 2113 and the pawl 2112, the arm 212 is only driven by the gear wheels during the linear movement of the hand.

The kinematic free chain of nil ratio driving the hand 213 comprises an intermediate wheel 2137 on a spindle 2141, driven by the fixed pinion 2024. This wheel 2137 engages with a pinion 2135 fixed to another pinion 2133, the assembly being idly mounted on the spindle 211. The pinion 2133 drives a toothed wheel 2134 mounted on a spindle 2155 which is carried by the arm 212. The wheel 2134 engages with a pinion 2132 mounted on the spindle 2126 also carried by the arm 212. On the pinion 2132 is wedged the hand 213 by means of locking washers 2131. The pinions 2132 and 2133 have an equal number of teeth. The overall transmission ratio is therefore equal to 1:1, as the central pinion 2024 is fixed, the mean angular movement of the hand is nil.

This chain allows the hand 213 to remain horizontal during the rotation of the plate 20. However, as will be explained in connection with the functioning of the apparatus, it is necessary that the handle should be vertical during the positioning of the cap on the neck of a bottle. To this end, a planar differential system is used

which allows the chain to be given an angular movement with an amplitude of 90° produced by a fixed cam 2023. The spindle 2141 is therefore mounted in the center of linked rocking bars 2142 joined on one side to a small lever 2143 through a spindle 2144 and, on the other side, to a spindle 2147 on a large lever 2146 carrying a roller 2149 able to roll on a fixed cam 2023. The small lever is jointed at its free end to the plate 20 through a spindle 2145 while the large lever 2146 at its free end is joined to the spindle 2116 which already carries the intermediate pinion 2115. The cam 2023 consists of two parts having the form of staggered circular sectors; when the roller 2149 rolls on the sector 20231 of large radius, the hand is vertical and directed downwardly; when the roller 2149 rolls on the sector 20232 of small radius, the hand 213 is horizontal. These two circular sectors are joined by two curves 20233 and 20234 corresponding one to the upward swing and the other to the downward swing of the hand.

The hand 213 carries a slide-bar 2138 at the end of which is mounted a guide 2139 for maintaining the orientation of the cap during its transfer and positioning, on the neck of the bottle. On the slide bar 2138 can slide a suction block 215 which carries a rubber sucker 2151 (FIG. 1) capable of retaining the caps by suction, a coil spring 2156 urges the suction block 215 towards the opposite end of the slide bar 2138 to the end carrying the guide 2139.

The whole assembly constituted by the hand, the slide bar and the sucker must allow the descent and positioning of a cap on the neck of a bottle. To this end, the suction block 215 carries a spindle 2154 on which a roller 2153 can turn driven by a fixed exterior cam 2152. On the other hand, the arm 212 carries a roller 2124 coming into contact at the lower part of its route with an exterior cam 2125. The profile of the latter cam is determined in such a way that the horizontal projection of the displacement of the spindle 2126 during 1/8 of the rotation of the plate 20 should be a rectilinear and uniform movement, identical with that of the bottles, described below.

The mounting of the cams 2125 and 2152 is illustrated in FIGS. 21 and 22. The cam 2125 is mounted to the right of the turntable constituted by the rotatable plate 20 and is fixed to a frame 2002 by supports 2003. The cam 2152 is fixed a long way in front of the frame 2002 by a cross-piece (2004) bolted down onto the latter.

A torsion spring 210 holds the roller 2149 against the cam 2023, the roller 2024 against the exterior cam 2125 and the pawl 2112 against the tooth 21131 of the ratchet wheel 2113. It also engages the set of gear wheels. This simultaneous action is made possible by the fact that the average angular movements are nil, and in consequence equal and in the same direction. The spring is supported firstly in a groove made in the pinion 2133 whose movement is linked with that of the hand, and secondly in a hole made in the cross-bar 2121 which is clamped on the spindle 211 whose movement is linked with that of the arm. This spring must be tightened with an accuracy corresponding to a gear tooth, pushing back the rocking levers 2142 so that the teeth of the intermediate wheel 2137 are disengaged from those of the pinion 2024.

The sucker 2151 is connected to a source of vacuum by way of a distributor 2161 rotary joint 2162 (FIG.

20) drilled into the shaft 211 and a flexible exterior tube 2164. The distributor 2161 is driven in the direction of the vacuum by a roller 2165 able to come into contact with a cam 2166. Each time the roller 2165 passes in front of the cam, it connects its exit, i.e., the sucker 2151 with the source of vacuum and provides for the suction of a cap.

The return of the distributor 2161 is pneumatic and controlled by a second distributor 2171 with a return spring, fed with compressed air through a central shaft 201 and a rotary joint. This distributor 2171 is controlled by an adjustable cam 2172 moving on its control roller 2173. The cam 2172 is held on a curved bar 2174 by a strap 2175 which permits its angular adjustment. The distributor is activated by each turn of the plate 20, that is to say every two cycles, and it allows the passage of air to the pilot of the distributor 2161 by which it recalls, if need be. In such a case, the circuit of the latter distributor is inverted so that air reaches its exit and insures the rapid displacement of the cap by blowing.

The two devices 1 and 2 described above are mounted (FIG. 1) on a common crosshead 2300 whose height is adjustable by means of a wheel 2301. The crosshead is slideable on vertical columns 2302, its movement being controlled by a threaded rod 2303 clamped onto the wheel 2301 and engaging with a nut 2304 fixed to or integral with the crosshead.

The device 3 for transferring bottles comprising (FIGS. 23 to 32) a linear bottle transporter 317, and six carriages 31 to 36 each carrying a gripping device and traveling on a track 37.

The linear transporter 317 comprises (FIGS. 1 and 32) a standard belt endless chain the speed of which is synchronized as was explained with reference to the device for cap transfer. The synchronization of the introduction of bottles at the entrance is insured by a variable pitch feed screw 3171. The transporter 317 passes in front of the device 2 which deposits a cap onto the mouth of each bottle.

The carriages 31 to 36 are identical, the description of the carriages 32 to 36 being obtained by replacing, in the description of the carriage 31 which follows, the various reference numbers by the number of the carriage under consideration.

The carriages 31 has a body 310 comprising a cylindrical side wall 3101 and an upper wall 3102 provided with a bearing 3103 whose axis is parallel with the generator of the side wall 3101. This bearing carries two coaxial shafts, an interior shaft 311 and a hollow exterior shaft 312. The interior shaft 311 carries at its upper end jaws 3111 and at its lower end a lever 3112 provided with a roller 3113; in the same way, the hollow exterior shaft carries at its upper end jaws 3121 able to engage with the jaws 3111 so as to pick up a bottle for capsuling, and at its lower end a lever 3122 provided with a roller (3123). Inside the body 310 is fixed a jack (313) with a horizontal spindle 3131 drawn back into a closed position by a spring 3132. The spindle of this jack carries a small push-rod (3133) with slots 3134 and 3135 in which the rollers 3113 and 3123 can move. The speed of opening of the lever is regulated by a nozzle 3136 fed with compressed air by a port 3137 to which a flexible hose 3138 is connected.

The upper wall 3102 of the body 310 also carries two vertical spindles 314 and 315 each provided with a roller 3141 or 3151 and a small push-rod 3142 or 3152, the latter carrying a second roller 3143 or 3153. These

rollers are horizontal and situated in the same horizontal plane; when the small push-rods 3142 and 3152 are aligned and maintained under pressure by means of a shock-absorbent rubber spring, the spindles of these 5 rollers are in a vertical plane situated near the side wall 3101 and, more precisely, near a straight-line part of that wall. On the other side, the body 310 carries a vertical roller 3104 situated in a vertical plane equidistant from the spindles 314 and 315. These two spindles also 10 carry a cross-bar 3161 to which is linked a small push-rod 3162 attached to a chain 372 described below.

The track 37 on which the carriages move has a chassis 370 comprising two horizontal plates 3701 and 3702 fixedly joined to each other. The higher horizontal plate 3701 serves as a track for the vertical rollers such as the roller 3104 of the gripper carriages. It also carries a closed in slot 371 to guide the four vertical rollers, such as the rollers 3141, 3143, 3151 and 3153, carried by the carriages. The slot 371 comprises:

20 a rectilinear part 3711 parallel with the chain 317 for feeding the bottles;

a curved part 3712 with its concavity turned towards the inside, corresponding to the movement of the bottles towards the bottle capping machine;

25 a curved part 3713 with its concavity facing the outside the center of this part coinciding with the rotational axis of the heads of the capping machine; the bottles which have arrived at this point move at an angular and tangential speed equal to that of the capping heads; and

30 a part 3714 joined to the beginning of the rectilinear part 3711.

The carriages are drawn (FIG. 28) by a chain 372 35 moving on three wheels 3721, 3722 (shown on FIG. 29) and 3725 (illustrated by FIG. 30). The wheel 3721 is fixed on a spindle 3724 driven by a control chain synchronized with the control of the movements of the assembly.

40 The feeding of the carriages with compressed air takes place from a distributor (FIGS. 29 to 31) comprising a fixed plate 373 joined to the lower plate 3702 of the chassis 370 by a support 3735 and a turntable 374 wedged on a vertical shaft 3747 turning in the fixed

45 plate and carrying a sprocket wheel 3748 driven by a wheel 3725 itself driven by the spindle 3724. The shaft 3747 is driven by the gear wheels 3725 and 3748, at a speed of one turn per six bottles passed through. The mobile plate 374 is maintained in close contact with the fixed plate 373 by a spring 3749.

The turntable 374 has six air distribution ports 3741 to 3746, while the fixed plate has four pipes 3731 to 3734, of which the pipes 3731 and 3733 are connected to the main compressed air supply, the pipe 3732 is connected to the supply through an electro-valve (not shown) and the pipe 3734 is open to the surrounding atmosphere. The connection of one of the six air distribution orifices 3741 to 3746 with one of the pipes 3731 to 3754 brings about, according to the choice made,

55 60 the feeding or the opening to the atmosphere of the carriage jacks, such as the jack 313. The turntable 374 has six air distribution ports 3741 to 3746, while the fixed plate has four pipes 3731 to 3734, of which the pipes 3731 and 3733 are connected to the main compressed air supply, the pipe 3732 is connected to the supply through an electro-valve (not shown) and the pipe 3734 is open to the surrounding atmosphere. The connection of one of the six air distribution orifices 3741 to 3746 with one of the pipes 3731 to 3754 brings about, according to the choice made, the feeding or the opening to the atmosphere of the carriage jacks, such as the jack 313.

The device for bottle transfer herein described has the object of presenting the bottles, topped with their caps, which are presented in a definite way, to a bottle capping machine 4 of the crimping type. This machine is of a standard type but contains no device for orienting the bottle, and is adapted to place the caps in such

a way that the pleating takes place outside the zone covered by the markings.

The bottle capping machine is represented schematically on FIG. 32 and does not require a detailed description. It will merely be observed that it involves a horizontal turntable 47 which is roughly circular and is rotatable about a vertical shaft 471. The table 47 carries six supports 41 to 46 each one of which can be occupied by a bottle.

The crimping of the caps takes place in two stages, by way of a head combined with two concentric posts which are not shown, of which one insures the crimping pleating, that is to say, the formation of four pleats, the other being responsible for the flattening of these pleats on the neck of the bottle. Each one of these heads is carried by the stem of a vertical pneumatic jack. The first station comprises four jaws exerting a strong radial pressure, and stamps the caps to form two pairs of equal surfaces the surfaces being separated from one another by four pleats parallel with the generators, and the pleats absorbing the excess of metal. The second station flattens the pleats formed by the first to give to the dressing of the bottle a homogeneous appearance. The pleats at the edge of the printed area are flattened to one side and to the other of the latter.

An auxiliary chain 48 preferably of the same type as the chain 357 but much shorter, and a revolving synchronized cam 483 insure the exit of the finished bottles which two deflectors 481 and 482 guide towards the chain 357 which evacuates them.

The functioning of the apparatus may be explained as follows:

The caps are delivered nested one inside the other to form "sticks" 91. The caps in question are of an asymmetric type, i.e., having a beak, and have a circular cross-section for 270°, joined to two straight portions which are roughly perpendicular. A stick is placed in the groove 11 of the device 1, the beaks of the caps lying within the groove 11 which is correspondingly shaped.

The continuous rotation of the chain wheel 1148 entrains via the bevel gear 1147, the eccentric plate 1143. The latter, with the help of the tie rod 1144, transmits an intermittent movement to the lever arm 1142, and, in consequence, to the rollers 1121 and 1131 which drive the conveyor belts 112 and 113. The stick of capsules 91 therefore moves forward with an intermittent linear movement.

The advance of the stick is limited by the forward stop 1331 controlled by the jack 132. Thus, the first cap is placed in position under the distributor 13; the stop 1331 is then raised by the return of the jack shaft 132. This also brings about the raising of the corners 1332 and 1333 which, working on the rollers 1341 and 1342, make the grip supports 1343 and 1344 pivot around their respective spindles 1345 and 1346 and hence cause the coming together of the grips 1347 and 1348. These last lightly compress the stick at the back of the cap 913 to be distributed, so as to trigger off, by elastic deformation, two actions on the one hand allowing the introduction of air jets inside the capsule, via the nozzles 1351 and 1352, and on the other hand insuring that the remainder of the sticks stay in place. Thus, the cap is propelled to the left of FIGS. 1 and 2, and can be taken up by the device 2 for the transfer of capsules.

The stop 1331 has returned to its high position: a new cycle is ready to commence.

The control device 12 prevents the stick of caps from breaking contact with the groove 11, while the vane 5 1117 goes into action after the sucking of the first capsule by the suckers 1351 and 1352 and has to maintain the cap to be distributed in a horizontal position until the stop 1331 has dropped back to its low position.

The device 2 for cap transfer picks up and drops two 10 caps in the course of a complete cycle of the turntable 20, one of the caps being transferred by the device 21 and the other by the device 22.

The uninterrupted pulling off of a capsule which has 15 been stopped, demands a movement having at a certain point zero speed: therefore, the spindle 2126 mounted at the end of the arm 212 and on which the hand 213 is articulated, must describe a retrogressive curve. Moreover, as the cap is only slightly conical, the particular portion of the curve must be a horizontal straight line. This condition is fulfilled (FIG. 34) by the kinematic linking chain of -1 ratio combining the gears 2022, 2115 and 2114, the first having twice as many teeth as the third, and the distance between the spindles 201 and 211 being equal to that between the spindles 211 and 2126. Under these conditions, the spindle 2126 describes a horizontal straight line during that part of the cycle which corresponds to the picking up of the cap.

It is also important that, during another part of the 30 cycle corresponding to the positioning of the cap on the mouth of the bottle, the spindle 2126 should move at a speed whose horizontal component is equal to the speed of the moving bottles. This is possible providing that:

there is no attempt to keep the spindle 2126 on a straight line;

the average distance between the spindle 2126 and the horizontal line passing through the shaft 201 is roughly equal to one-half the distance covered during the time of transfer of a cap by the bottle; and

the length of the arm 212 and the distance between the spindles 201 and 211 are greater than that average distance.

45 The corresponding curve is complicated: it is described by the cam 2125. FIG. 33 represents the curve obtained; it is to be noted that the angular movement of the arm has the opposite sign to that defined with reference to the horizontal rectilinear movement; in continuing it to join the two parts, a mean angular movement of zero is obtained on a rotation of the turntable 20. The outline of the cam is obtained as follows:

55 A circle is traced, whose center is on the axis of the shaft 201 and whose radius is equal to the distance between the shafts 201 and 211: this circle is the geometric locus of the successive positions of the shaft 211. The locus of the positions of the spindle 2126 is then traced. As long as the pawl 2112 of the hub 211 is in contact with the only tooth of the ratchet wheel 2113, the locus is the horizontal line of the shaft 201, for the distance between the spindles 211 and 2126 is equal to that between the shafts 211 and 201 and the angles are equal and in the opposite direction. From the moment 60 at which this contact is broken, the locus depends on the outline of the cam and it must be such that the horizontal component of the moving speed of the spindle 2126 remains constant. The circle 211 is therefore di-

vided into equal segments whose apices represent successive positions of the spindle 211. The equidistant vertical right angles on which the spindle 2126 must be found when it occupies the corresponding positions are then traced. These are at a distance from the corresponding apex of the circle equal to the radius of the latter. The outline of the cam is deduced by positioning the rollers 2124 for each position of the arm 212, and tracing the envelope of the roller positions.

The kinematic chain according to FIG. 35 which controls the movements of the hand 213 must allow the following movements: the hand must present itself horizontally at the moment the cap is taken up, stay thus for substantially 120° of the movement of the table 20, rock towards the base of a right angle, stay there for substantially 105° of the movement of the table 20, then return to the horizontal line by a rocking upward movement through a right angle, in a direction opposite to that of the previous rocking movement. Thus, a total angular movement of nil in a rotation of the table 20 is achieved. During the greater part of the cycle, the instantaneous movement is also nil.

This is carried out by an assembly of six independent gears, with a nil ratio the assembly comprising a gear 2024 fixedly mounted on the shaft 201, the gear 2137 and 2135, the gear 2133 which is keyed to the preceding gear and like it is idly mounted on the spindle 211, the gear 2134 and the gear 2132 which is keyed to the spindle 2126; the gears 2024 and 2135 on the one hand, and the gears 2133 and 2132 on the other hand have the same number of teeth.

The rocking by 90° is obtained by lateral displacement of the intermediate wheel 2137. This wheel pivots on a spindle 2141 fixed in the middle of one of the large sides 2142 of a distorted quadrilateral made up of the rocking levers 2142, the small lever 2143 and the large lever 2146, the fourth side being constituted by the table 20. The large lever carries at its end the roller 2149 which roll on the fixed cam 2023. The middle point 2141 of this system describes a figure eight of which a very small part on either side of a point of inflection can be likened to a right angle. The quadrilateral can be much further deformed so as to bring the point onto a very curved part of the figure eight. The gear wheel 2137 is thus retracted and its teeth leave those of the central pinion 2024; this position, which is never attained in normal operation, allows easy adjustment of the tension spring 210.

The two kinematic chains, that of the arm and that of the hand, necessarily share a common point constituted by the spindle 211. It is therefore possible to use only a single tension spring 210 to apply the roller 2149 to the cam 2023, the roller 2124 to the cam 2144 and the pawl 2112 against the tooth 21131 of the ratchet wheel 2113 at the same time as reengaging the gears.

The movement of the sucker 2151 relative to the hand 215 is governed by the following considerations. The displacement of the spindle 2126 of the hand is made during the placing of the cap on the bottle, with a horizontal component of constant speed and with a vertical component which cannot be controlled, depending on the form of the exterior cam and unsuitable to insure the correct descent of a cap onto a bottle. In any case, the presence of the guide 2139 makes undesirable the complete descent of the hand over the bottle. The sucker is therefore mounted on the servo-slide

bar 2138, which allows on the one hand the accelerated and then decelerated descent of the cap onto the bottle, and on the other hand the immobility for a definite time of the sucker with respect to the stick of caps during the taking up of the latter, by a relative movement annulling that of the hand.

In order to understand fully the principle of this movement, one may imagine the hand 213 in a fixed position while the arm 212 swings from one side to the other.

The coordination of the various movements is carried out as will be explained below. The movements and positions are marked by the angle of rotation of the table 20 from an initial position corresponding to the end of the rocking movement towards the top of the arm 212 which is called the zero degree position.

At the 0° position, the spindle 2141 of the toothed wheel 2137 is displaced with respect to the plane of the spindles 211 and 201 by a linear distance corresponding to an angular movement of 45° of the hand, with the pulley leaving at that moment the part 20233 of the cam 2023 to start on the semi-circular part 20232. The gears 2024 and 2137 having engaged, and the gears 2135 and 2133 being keyed to one another, the gears 2134 and 2132 bring the hand to a horizontal position at which it is maintained, while the gears 2022, 2115 and 2114 transmit to the spindle 2126 a horizontal movement, because the pawl 2112 touches the tooth 21131 of the ratchet wheel 2113. During 60° of the rotation of the table 20, this movement is made in the direction of the cap 913 which is presented by the orientation device 1. The guide 2139 embraces the capsule, the sucker 2151 being maintained in a rearward position on the slide bar 2138 by the movement of the spring 2156. At about 50°, the pulley 2165 of the distributor 2161 comes into contact with the cam 2166 and carries out the vacuum action; the sucker sucks in the cap 913. At 60°, the movement of the spindle 2126 is reversed, the spindles 201, 2114 and 2126 being then aligned, and the hand and the sucker retaining its cap withdraw until the angle through which the table 20 has travelled reaches 120°.

At that moment, the roller 2149 leaves the part 20232 of the cam 2023 to go on to the part 20234 which induces the translation of the spindle 2141 of the gear 2137 by a distance corresponding to a downward rotation through 90° of the hand 213. On the other hand, the cam 2125 acts on the pulley 2124 causing the arm to turn, thus separating the pawl 2112 from the tooth 21131 of the ratchet wheel 2113.

When the table has travelled through an angle of 187°, the roller 2149 reaches the part 20231 of the cam 2023 and rolls there: the wheel 2137 remains engaged and the hand remains in a vertical position. At the same time, the cam 2125 continues to act on the roller 2124 and transmits to the spindle 2126 a movement whose horizontal speed is equal to that of the bottle to be capped. The pulley 2153 carried by the suction block 215 comes into contact with the cam 2152 so that the block 215 and the nozzle advance on the slide bar 2138 in the direction of the guide 2139 which has capped the mouth of the bottle. When the nozzle comes to the end of its course, the roller 2173 of the distributor 2171 comes into contact with the cam 2172, breaking the vacuum and causing a rush of air which separates the cap from the sucker. The rush of air is stopped as soon as the roller leaves the cam. When the sucker reaches

its lowermost position, the spring 2156 makes the sucker retreat following the profile of the cam 2152.

At the same time the table reaches an angle of 292.5° and the roller 2149 comes on to the part 20233 of the cam 2023 so that the hand pivots from 90° towards the top. The cam leaves the roller 2124, the pawl 2112 returns into contact with the tooth 21131 of the ratchet wheel 2113, and the table continuing its rotation returns to its starting position.

The device 22 for cap transport functions exactly like the device 21 but is displaced therefrom by 180° on the turntable 20.

It is to be noted that the assembly for cap distribution is activated by a detector capable of sensing the presence of a bottle and will only allow the feeding of the assembly if a bottle is present to receive a cap. If no bottle is present, there is no vacuum, so that the cap 913 is not sucked up by the sucker, nor is there an interruption of the vacuum if the latter is already established so that the cap previously sucked up is not set down. Should a bottle arrive without a cap, a proximity detector causes the pincers to release the bottle, placing it on a reject line and thus preventing its entry into the bottle-capping machine.

While the capsules are being released and transferred by the apparatus 1 and 2, the bottles are being placed in position, and undergo a linear translation at a speed equal to the horizontal component of the speed of the spindle 2126 of articulation of the hand 213.

A bottle arriving at the entrance to the apparatus 3 is drawn by the translation chain 317, then taken over by the variable pitch feed screw 3171, which draws it to the entrance end of the linear part 3711 of the slot 371, between the open jaws 3111 and 3121 of the carriage 31. The corresponding orifice 3741 of the mobile turntable 374 of the compressed air distributor is opposite the channel 3731 of the fixed plate 373 so that the compressed air penetrates into the jack 313, which by acting on the rollers 3113 and 3123 causes the closure of the pincers constituted by the jaws 3111, 3121. From then on, the bottle is immobilized during rotation and its orientation will be that of the pincers at the different stages of its movement. The bottle is now taken along by the pincers and leaves the chain 317.

The pincers 3111-3112 deposit the bottle in a support 41 of the bottle-capping machine 4; the orifice 3741 of the distributor turntable is opposite the channel 3734 causing the jack 313 to be open to the surrounding air, and by the action of the return spring 3132, causes the withdrawal of its shaft and the opening of the pincers 3111, 3121. The carriage continues its movement until it reaches the linear part 3711 of the slot 371 and seizes a new bottle.

In the bottle-capping machine, the bottle passes under the combined heads with the concentric stations for pleating-crimping and for flattening of the pleats, and is then sent into the moving chain 317 by the action of the deflectors 481-482 of the revolving cam 483 and the auxiliary chain 48.

The drawing chain 372 passes over the wheels 3721, 3722 and 3723 of which the first is driven by a motor. This chain does not follow precisely the outline of the slot 371 firstly because its length cannot be adjusted to any desired value, and also because the shape of the supports 41 to 46 of the bottle-capping machine does not allow insertion at a constant speed with an entry path having a small radius; the chain is therefore pro-

gressively withdrawn from the track of the slot 351 in such a way as to increase the slope of the small tie-rods 3162, 3262, 3362, 3462, 3562, and 3662, which induces an acceleration in the movement of the bottle and allows its easy introduction into the support.

The apparatus described is remarkable for its small bulk, the possibility of its being totally automatic and the fact that it does not require any auxiliary means for orienting the cap.

The invention is applicable to the placing of sealing caps on bottles for gasified wines such as champagnes, sparkling wines or cider.

It will be understood that changes may be made in the details of construction, arrangement and operation without departing from the spirit of the invention, especially as defined in the following claims.

I claim:

1. A device for the transfer of sealing caps comprising a hand carrying suction means for holding a cap during transfer, an arm held onto a first spindle, the hand being articulated to its support arm by a second spindle, a turntable held on a shaft which is pivotable in a fixed hub and carrying the first spindle idly mounted thereon, a kinematic chain of -1 ratio controlling the movements of the arm through gearing which causes the chain to be engaged during the taking up of a cap by the suction means and to be disengaged while the cap is deposited onto the neck of a bottle, an exterior cam controlling the movements of the arm, and a kinematic chain of nil ratio maintaining the position of the hand through a plane differential allowing the introduction into the chain, during the placing of the cap of an angular movement with an amplitude of 90°, produced by a fixed cam.

2. A device as claimed in claim 1 in which the kinematic chain of -1 ratio controlling the movements of the arm comprises a toothed wheel mounted on the fixed hub, an intermediate pinion engaging with the toothed wheel and driving a pinion keyed to a one tooth ratchet wheel and idly mounted on the first spindle, a hub carrying a pawl engageable with the ratchet wheel and mounted on the first spindle which carries the arm, the toothed wheel and the pinion having a tooth ratio of 2:1 and the distance between the first and second spindles and between the first spindle and turntable being equal.

3. A device as claimed in claim 2 in which the arm carries a roller able to roll on the exterior cam.

4. A device as claimed in claim 1 in which the kinematic chain of nil ratio maintaining the position of the hand contains a pinion mounted on the fixed hub, an intermediate gear wheel engaging with this pinion and driving a first pinion keyed to a second pinion and idly mounted therewith on the first spindle, a toothed wheel engaging with the second pinion and driving a third pinion mounted on the second spindle, which is carried by the arm and on which the hand is mounted, the overall transmission ratio of the assembly of six wheels and pinions being 1.

5. A device as claimed in claim 4 in which the plane differential of the kinematic chain of nil ratio is constituted by an articulated quadrilateral comprising a compensation bar carrying the intermediate gear wheel and articulated on one side to a small lever and on the other side to a large lever carrying a roller able to roll on the fixed cam, the two levers being articulated on the turntable.

6. A device as claimed in claim 1 in which the fixed cam has a circular part of large radius, corresponding to the hand being in a vertical position directed downwardly, a circular part of small radius corresponding to the hand being in a horizontal position, and two joining parts and corresponding to the rocking of the hand, one towards the top and the other towards the bottom.

7. A device as claimed in claim 1 in which the mounting of the suction means on the hand comprises a slide bar carrying a guide able to orientate during its transfer and positioning on the neck of a bottle, a suction block slideable on the slide-bar and carrying the suction means, a roller carried by the suction block and engageable with a cam controlling the movement of the suction block on its slide bar and a recall spring for the suction block biasing the block to a retracted position.

8. A device as claimed in claim 1 comprising a torsion spring applying the roller of the large lever onto its cam, the roller carried by the arm onto the exterior cam and the hub pawl against the one tooth ratchet wheel.

9. Apparatus for the transfer of bottles adapted to operate with the cap transfer device claimed in claim 8, comprising a belt or chain conveyor means, a variable pitch screw which regulates the entry speed of the bottles, a rolling track provided with a continuous guide slot, at least one carriage carrying two jaws constituting a pair of pincers able to grasp a bottle, and at least two horizontal guide rollers engaged in the slot in such a way as to insure the guiding of the carriage, and an endless chain for drawing the carriages along.

10. Apparatus as claimed in claim 9 in which the guide slot comprises a rectilinear part parallel with the chain, a frustocurved part concave towards the interior, corresponding to the displacement of the bottles towards a bottle capping machine; a second curved part concave towards the outside with its center coinciding with the rotational axis of the heads of the bottle capping machine, the bottle arriving at this point moving at a speed equal to that of the heads, and an intermediate part joining with the beginning of the rectilinear part.

11. Apparatus for bottle transfer as claimed in claim 10 in which each carriage is joined to the chain by a

small articulated push rod which allows the chain to be progressively withdrawn from the outline of the slot so as to increase the slope of the small push rod, thereby effecting an acceleration of the movement of the bottle at its entrance to the bottle capping machine.

5 12. Apparatus for bottle transfer as claimed in claim 11 in which the carriage carries a bearing in which two hollow co-axial shafts, an interior shaft and an exterior shaft are rotatable, the shafts being respectively joined, 10 at one of their ends each to one of the jaws, and at their other ends each to a lever carrying a roller, a jack being provided which is restrained by a spring and whose stem carries a small push rod provided with slots in which the shaft rollers are slideable, and the arrangement being such that the compression of the jack induces the closure of the pincers constituted by the jaws.

13. Apparatus for bottle transfer as claimed in claim 12 in which the carriages carry a pair of fixed horizontal rollers, a pair of mobile horizontal rollers, each of 20 which is mounted on a small push rod articulated onto the spindle of a fixed roller, the two pairs of rollers being engaged in the guide slot of the track.

14. Apparatus for bottle transfer as claimed in claim 25 13, comprising a compressed air distributor, having a fixed plate provided with four channels, a first and a second channel being connected to a compressed air supply, a third channel being connected to the second via a valve, and the fourth channel being connected 30 with the surrounding atmosphere; and a mobile plate carrying six air distribution parts, joined to the jacks of the carriages capable and of being placed in front of one of the four channels of the fixed plate.

15. A device as claimed in claim 1 in which a nested 35 stick of beaked caps is positioned in a channel of corresponding shape with the beaks extending into the channel; in which the caps are removed from the stick one by one by means of the transfer device, and each is positioned on the mouth of a bottle according to a constant orientation; and in which the bottles are transferred to a bottle capping machine in such a way that the beaks of the caps have a predetermined orientation, allowing crimping of the caps onto the bottles without affecting any matter printed on the caps.
